(57) **CLAIM**

The ornamental design for a stand for electronic device, as shown and described.

DESCRIPTION

FIG. 1 is a front perspective view of a stand for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front perspective view thereof, in which a display device is shown in broken lines as an example environment.

The broken lines in the drawings illustrate portions of the claimed design and the environment of the claimed design and form no part thereof.

1 Claim, 6 Drawing Sheets

FIG. 1

FIG. 2

FIG. 3

FIG. 4

FIG. 5

FIG. 6

FIG. 7

FIG. 8
